IRONING BOARD COVER

Joseph G. Adiletta, Riverside, and Theodore Descovich, Springdale, Conn., assignors to Pall Corporation, Glen Cove, N.Y., a corporation of New York
 Original application Oct. 29, 1962, Ser. No. 233,572, now Patent No. 3,245,161, dated Apr. 12, 1966. Divided and this application Feb. 21, 1966, Ser. No. 548,816
 2 Claims. (Cl. 38—140)

This application is a division of U.S. application Ser. No. 233,572 filed on Oct. 29, 1962, now U.S. Patent No. 3,245,161 issued on Apr. 12, 1966.

This invention relates to ironing tables and more specifically to improved ironing table construction and to covers therefor.

It is a primary object of the invention to provide an ironing table or board of improved configuration in which a single ironing surface incorporates a bifurcated portion upon which sleeves and other tubular garments or articles may be ironed as well as providing an ironing surface for general purpose ironing.

It is another object of the invention to provide a novel pad and cover combination including a cover cloth which resists scorching and burning for an indefinite period of time under normal ironing temperatures and a resilient pad for said cover which is sufficiently resistant to heat to avoid discoloration and loss of resiliency. The combination provided is such that even after prolonged periods of use under the hottest of ironing conditions, it does not lose its resiliency nor result in unsightly discoloration from heat scorching.

It is a further object of the invention to provide a novel ironing table having a bifurcated sleeve portion as an integral part of the main ironing surface coupled with a novel means for peripherally securing a pad and cover in wrinkle-free relationship on the board.

Additional objects and advantages provided by the invention will become apparent from the following description of the invention taken in conjunction with the various figures of the drawing in which:

FIG. 1 is a perspective view of an ironing table surface constructed in accordance with the inventive teaching provided with a support structure of conventional arrangement.

FIG. 2 is a fragmentary side view of a pad combination according to invention which includes a fiberglass mat interposed between the cover and waffle-weave pad.

FIG. 3 is a view taken substantially along line 3—3 of FIG. 1 illustrating the various substrates on a metal surface and one method of securing the pad and cover to the ironing surface.

FIG. 4 is a bottom view of a metal ironing table surface illustrating a method of securing wood strips at the underside of the board to facilitate the attachment of the cover.

FIG. 5 illustrates an alternate means of securing the pad and cover to a wood surface.

FIG. 6 illustrates an arrangement in which the space between the bifurcated arms may be filled by a removable insert to provide a substantially uninterrupted ironing surface.

FIG. 7 is a view taken substantially along line 7—7 of FIG. 6.

The invention essentially provides an improved structure in the ironing table art which offers the optimum in utility, service life, and convenience. It has heretofore been the practice in connection with ironing tables to use a separate board to iron tubular articles such as sleeves. This has necessitated the need for a separate board. A separate board is cumbersome; its presence together with various other items, including the main board itself, the iron and the article being ironed result in congestion in

the vicinity where ironing is taking place, and frequently is the occasion for accidents. By combining a pair of relatively narrow ironing surfaces formed integrally with the main ironing surface, a novel and useful and highly advantageous result is obtained.

The invention contemplates further the provision of a cover and pad combination which provide the optimum in cushioning for the ironing surface and which effectively resists scorching and burning. In this respect, the present invention employs the novel ironing covers disclosed and claimed in the pending application of J. G. Adiletta et al., S.N. 141,433, filed on Sept. 28, 1961, now abandoned. With the ironing surface covers disclosed in that application, the present invention combines a novel substrate padding to provide a combination which successfully prevents staining or discoloration occasioned by the use of conventional padding and hereto visible through the covers disclosed in the above application, S.N. 141,433.

Referring to FIG. 1 of the drawing, an ironing table comprising an ironing surface 10 is supported in a conventional manner as by supporting legs 11. The surface may comprise materials which are ordinarily used, e.g. wood, perforated metal or metallic mesh containing a sheet metal periphery, in accordance with the manner in which ironing surfaces are conventionally constructed.

In the table shown, the ironing table surface 12 of the invention comprises a perforated metallic structure having a bifurcated portion designated 13 which comprises a minor length of the total ironing surface and includes a relatively narrow portion 14, a wider portion 15 and the main board surface 16. The length 17 of the main board surface 16 is of substantially greater length than the bifurcated section.

In the preferred embodiment, a cotton padding 20 of conventional kind such as waffle pad is first placed on the ironing table. Upon this first pad is placed a heat barrier 21 which comprises a heat resistant material such as glass fiber wool. The strata 21 is heat cleaned or prebaked in order to remove ingredients, e.g. resins and other incorporated material, which upon heating tend to discolor and present an unsightly appearance and be visible through the surface cover cloth 22. The visibility of discolored material through the cover cloth has heretofore occasionally presented an unsightly appearance even though the cover cloth itself has not been affected. The cover cloth 22 comprises the material disclosed and claimed in the aforementioned application S.N. 141,433. Preferably, the pad 20, heat barrier 21 and cover 22 are sewed as at 23 into an integral structure as illustrated in FIG. 3, around the periphery of the surface with the depending skirt portion 24 preferably comprising a material more flexible than the ironing cover 22. The pad 20, heat barrier 21, and cover cloth 22 are suitably secured to the ironing surface in a convenient manner as by means of continuous molding (not shown) suitably fastened to the table or as illustrated in FIG. 3 by driving staples 26 (through the cover skirt) into wood blocks or strips 25 as shown in FIG. 4 which are attached to the underside of the table 12.

In the embodiment shown in FIG. 5, the ironing surface comprises a wood table 27 containing the pad and cover arrangement described in conjunction with FIGS. 1 and 2. The cover and pad are secured to the surface by means of a plurality of clips 29 spaced peripherally around the board in a groove 28 formed in the underside of the table top.

Illustrated in FIGS. 6 and 7 is a suitable arrangement for removably positioning an insert 35 in the space between the arms 14 and 15 to afford a substantially uninterrupted surface when the surface is used for the ironing of large articles of substantially uniform yardage, e.g.

sheets or drapes. In such cases, the entire length of the board may be employed and the ironed portion may be uniformly draped after ironing behind the board or as shown in FIG. 11 into the opened receptacle formed by the cover. Any suitable device may be used to store and secure the insert 35. As shown, the insert 35 may be held at one end 37 with a spring 36 of relatively light

temperature to which the cotton waffle-weave pad is subjected using the combination of the invention which interposed a fiber glass pad at heat barrier between the cover of the kind disclosed and claimed in S.N. 141,433. In each case, the cover is the same and readings are taken for each strata after the iron is applied at full heat for 30 minutes.

	Run #1		Run #2		Run #3		Run #4		Run #5		Run #6	
	Comb.	Temp.	Comb.	Temp.	Comb.	Temp.	Comb.	Temp.	Comb.	Temp.	Comb.	Temp.
Cotton waffle-weave base	(1)-----	340	(1)-----	360	(1)-----	330	(2)-----	265	(2)-----	245	(2)-----	247
Barrier-----	None-----		Steel screen.	395	Steel wool.	395	(3)-----	310	(4)-----	305	(4)-----	308
Resin coated glass cover. ⁵	-----	440	-----	440	-----	450	-----	450	-----	450	-----	450

¹ Darkly scorched within 5 min.

² Unscorched even after 30 min.

³ Fiber glass pad (untreated).

⁴ Fiber glass (prebaked).

⁵ Cover for Runs #1-5 comprises a material prepared in accordance with Example 4 of U.S. patent application S.N. 141,433, i.e. woven glass fabric coated with silicone rubber.

tension. The spring is attached at the other end to the board at 38. The strap 39 may be employed to aid in holding the insert 35 in its retracted position. When the insert is used to form an extension of the ironing surface, it is only necessary to pull it in the direction of the arrow against the force of spring 36 to a position slightly beyond the point where it is held in abutting position in the space between arms 14 and 15. The tapered edges of the padded and covered insert 35 conjointly with the edges of the bifurcated structure comprising arms 14 and 15 and spring 36 provide suitable retention for the insert 35.

An additional feature of the invention comprises the novel ironing cover and pad combination. This is preferably combined into an integral structure as shown in FIG. 2. An essential feature of the novel cover-pad combination lies in the heat barrier.

The following table illustrates the significantly lower

⁶ Cover in Run #6 comprises woven glass fabric as prepared in accordance with Example 1 of U.S. patent application S.N. 141,433, i.e. polytetrafluoroethylene resin on glass woven fabric.

NOTE.—Generally scorching of cotton waffle-weave is noticeable at temperatures in the range of about 300-325 after about 5 minutes duration.

Various additional modifications may be made in the details described in connection with the description of the invention without departing from the scope of the invention. Accordingly, the invention is not to be limited except insofar as is necessitated by the appended claims.

What is claimed is:

1. An ironing cover and pad combination comprising essentially a cotton waffle weave cushion pad base, an outer cover of a woven glass fabric impregnated with a resin selected from the group consisting of a fluorocarbon resin and silicone rubber and a heat barrier comprising a glass fiber mat interposed between said pad and said cover.

2. The cover of claim 1 wherein said cover, pad and heat barrier are sewed to form an integral structure.
